(57) **CLAIM**

The ornamental design for a bracket, as shown and described.

DESCRIPTION

FIG. 1 is a left perspective view of a bracket.

FIG. 2 is a right perspective view thereof.

FIG. 3 is a top plan view thereof.

FIG. 4 is a front elevation view thereof.

FIG. 5 is a rear elevation view thereof.

FIG. 6 is a right side elevation view thereof.

FIG. 7 is a left side elevation view thereof; and,

FIG. 8 is a partial left side elevation view thereof, taken along line 8-8 in FIG. 3.

The dashed broken line areas show portions of the bracket that form no part of the claimed design. The dot-dashed broken lines in FIG. 3 are for the purpose of illustrating where the view of FIG. 8 is taken from, and form no part of the claimed design.
